UNITED STATES PATENT OFFICE.

MICHEL G. FAGAN, OF TROY, NEW YORK.

DEVICE FOR BURNING AIR AND HYDROCARBON VAPORS.

SPECIFICATION forming part of Letters Patent No. 252,307, dated January 17, 1882.

Application filed May 13, 1881. (No model.)

To all whom it may concern:

Be it known that I, MICHEL G. FAGAN, of the city of Troy, county of Rensselaer, and State of New York, have invented a new and useful Improvement in Devices Constructed to Burn the Vapor of Hydrocarbon Liquids for Cooking and Heating, of which the following is a specification.

My invention relates to that class of devices designed to burn the vapors of hydrocarbon liquids by mixing them with the atmosphere, and to utilize the heat produced thereby for heating and cooking purposes.

My invention therefore consists in the novel construction and combination of parts, as will be hereinafter more fully set forth and specifically claimed.

In the accompanying drawings, forming a part of this specification, there are three figures illustrating my invention, in each of which the same reference-letters are used to designate the same parts.

Figure 1 shows in perspective the apparatus containing my invention. Fig. 2 illustrates in perspective, and as separated from the rest of the device, the receptacle constructed to contain the hydrocarbon liquid; it shows, also, the manner of forming vertical flues, and the position of the wicks placed vertically within the flues. Fig. 3 shows one of the wicks removed from the receptacle, and enlarged in proportion, to better illustrate it.

The several parts of the device are designated by letter-reference, and described as follows:

T' T' T''' denote three table-platforms, supported on the standards F'' and the feet L L.

The letter B designates a receptacle for hydrocarbon liquid, having a supply-orifice at d'', and which receptacle is secured in any suitable manner to the underside of the lower platform, T''; and P'' P'' designate two pipes connecting with the receptacle at their lower ends, and at their top, D, open, so as to discharge the air and vapor of hydrocarbon liquid beneath the boiler-holes O O, formed in the upper table-platform, T', where burned.

At S there is shown a place to apply clock mechanism to force air through the receptacle by means of the pipe P', which connects the latter with the former.

Within the receptacle B there are formed

the labyrinthine flues, designated at t, and they are produced by means of the vertical plates F F. Within these flues there are hung the wicks, 55 designated at a, which are made of a coarse fibrous material, and such as will by capillary attraction absorb and vaporize the fluid in the currents of air passing through the flues and open structure of the wicks. The flues designated at t are made to encircle the interior of the receptacle, so as to receive the air at the outer convolution of the flue, and to discharge it from the central termination of the flue shown at a''. 60

To force a current of air into and through the flues any of the well-known devices designed for this purpose may be used, my invention relating to a manner of utilizing a current of air under pressure for this purpose, 70 rather than to a means of producing it.

The operation of the combined parts is as follows: A current of air under pressure entering the pipe P' passes downwardly and into the receptacle B, thence through the flue t, at 75 the outer convolution of the latter, and it passes through its inner convolutions to the longitudinal center of the inclosure until it reaches the termination designated at a''. From this part of the flue t the mixture of air and vapor 80 rises through the pipes P'' P'', to be discharged and burned at the upper orifices of the latter, designated at D. At O'' O'' are shown valves formed in these pipes to close them when it is desired to extinguish the flame. While I have 85 herein shown two pipes, one may be used, if desired. At a the wicks are designated as being hung in the flues t t, and these wicks take up by capillary attraction the hydrocarbon liquid and evaporate it from their fibrous surfaces into the current of air passing through the flue. 90

I am well aware that there is no novelty in mixing air and hydrocarbon vapors to burn them for heating and cooking purposes. 95

I am also aware of the fact that fibrous material has been employed to vaporize hydrocarbon liquids for similar purposes, and that my invention is limited to the improved means invented by me to use these elements. 100

The platform T'' serves as an auxiliary shelf, to which the clock-work may be attached, as shown, and as a brace to steady the frame.

Having thus described my invention, what

I claim, and desire to secure by Letters Patent, is—

1. In a vapor-stove, the combination of the hydrocarbon-receptacle B, formed with the flues t, by means of the vertical strips F, and provided with the pendent wicks a, the pipes P'', and supporting-platform T', with openings O, substantially as and for the purpose set forth.
- 10 2. In a device for cooking by the combustion of a mixture of air and hydrocarbon vapor, the

combination of tables T' T'' T''', supported on the standards F'' F'' and on the legs L L L L, the hydrocarbon-receptacle B, having the flues t, wicks a, the air-inlet pipe P', and the outlet-pipes P'' P'', as shown, and as described.

Signed at Troy, New York, this 25th day of April, 1881.

MICHEL G. FAGAN.
